UNITED STATES PATENT OFFICE.

SAMUEL S. SARGEANT, OF NEWARK, NEW JERSEY.

DESIGN FOR HARNESS-MOUNTINGS.

SPECIFICATION forming part of Design No. 12,627, dated December 20, 1881.

Application filed June 20, 1881. Term of patent 14 years.

To all whom it may concern:

Be it known that I, SAMUEL S. SARGEANT, a citizen of the United States, residing at Newark, in the county of Essex and State of New Jersey, have invented and produced a new and original Design for Harness-Mountings; and I do hereby declare that the following is a full and exact description thereof, reference being had to the accompanying drawings, making part of this specification—

Figure 1 being a front view, and Fig. 2 an edge view, of a terret formed according to my design; Fig. 3, a front view, and Fig. 4 an edge view, of a fly-terret according to the same design; Fig. 5, a side view, and Fig. 6 a top view, of a check-hook according to the design; Fig. 7, a side view, and Fig. 8 a back view, of a post-hook according to the design; Fig. 9, a side view, and Fig. 10 a front view, of a union-hook according to the design; Fig. 11, a front view, and Fig. 12 a side edge view, of a martingale-ring formed according to the design; Fig. 13, a side view, and Fig. 14 a side edge view, of a swivel according to the design; Fig. 15, a side view, and Fig. 16 a front edge view, of a hook according to the same design.

Like letters designate corresponding parts in all the figures.

The main feature of this design for harness-mountings consists in the union or combination of two general forms—namely, the "band" or flat style and the "wire" or round style, the flat or band portions terminating in nearly semicircular outlines.

Thus in all of the articles, A represents the band portion of each, the outer surface being plane or flat transversely, while the longitudinal outline conforms to the shape of the article and to the design, as hereinafter set forth. The inner surface beneath the band-surface is rounded in cross-section, but is less than a semicircle, so that the part is thin compared with its breadth.

Also, in all of the articles, B represents the wire part. In general this wire part is round in section, and is smaller in diameter than the breadth of the band part, but greater than the thickness of the same. As to the location of

these two parts it may be stated generally that the wire part is next to the shank or holding part of the article, and the band part forms the terminal of each article, or the most distant from the shank or holder. The longitudinal conformation of the wire part corresponds with the form of the article in that part without special outline for this design; but in addition to the band and wire combination herein described, and represented in the accompanying drawings, I make the longitudinal outline of the band part of each article peculiar. Thus, near the terminals of the band part the outer or band surface is somewhat concave, or inwardly curved, while the middle or more remote part is convex, or outwardly curved. This applies where the form of the article admits this form. In simple hooks the form of the article itself does not permit this configuration to be applied, or only partially. Besides, a peculiar configuration is given to the part of each article where the shank or holder portion joins the wire part, consisting in a swell or boss, C, and terminating upward or from the shank in a rounded point, as at a, so that the whole forms approximately that of the small end of an oval, a heart, or an acorn. The form is clearly represented in the drawings. The simple hooks, from the direct mode of their attachment to the harness, have no part to which this boss is applicable, and in such articles this feature is omitted; and this part of my design may be omitted in all of the articles without detracting from the other features of the design; but for the most complete and perfect design I prefer this feature also.

What I claim as my design, and desire to secure by Letters Patent, is—

The design for harness-mountings herein shown and described, the same consisting of a combination of the band form A and wire form B.

The foregoing specification signed by me this 3d day of June, 1881.

S. S. SARGEANT.
